Primary Examiner — Kevin Rudzinski*Assistant Examiner* — Sean D Lough(74) *Attorney, Agent, or Firm* — Nelson Mullins Riley & Scarborough LLP(57) **CLAIM**

The ornamental design for a deactivator, as shown and described.

DESCRIPTION

FIG. 1 is an isometric view of a deactivator showing the new design; and,

FIG. 2 is a front view thereof.

The broken lines (where present) in all FIGS. illustrate portions of the deactivator that form no part of the claimed design.

1 Claim, 2 Drawing Sheets(56)
